United States Patent Office

Des. 182,864

Patented May 20, 1958

182,864

AUTOMOBILE

Karl Wilfert, Stuttgart-Degerloch, Germany, assignor to Daimler-Benz, Aktiengesellschaft, Stuttgart-Unterturkheim, Germany

Application May 4, 1956, Serial No. 41,355

Claims priority, application Germany November 14, 1955

Term of patent 7 years

(Cl. D14—3)

The essential part of my design is shown in full lines in Figure 1. The remaining parts of the automobile are of conventional construction.

I claim:

The ornamental design for an automobile, substantially as shown and described.
